UNITED STATES PATENT OFFICE

CHARLES A. HOWLAND, OF SCHENECTADY, NEW YORK

GAME

Application filed February 5, 1931. Serial No. 513,641.

The present invention relates to games and especially to games of the golf type wherein a ball is propelled by being struck by a suitable implement and caused to enter an opening or pocket.

One object of my invention is to provide an improved game of this type which may be played in a room on a carpet or rug, which may be utilized in connection with an indoor or outdoor miniature golf course, or which may be utilized in connection with a putting green or a green or greens of a regular golf course, and which may be played on an ordinary lawn.

Another object of my invention is to provide a hole or pocket for a golf game which is capable of being manufactured at low cost and which is set up easily in a room or out of doors on the ground.

A further object of my invention is to provide a hole or pocket for a golf game so constructed and arranged that added skill over that normally necessary is required in order to drive the ball into the hole or pocket.

Other objects and the advantages of my invention are pointed out more fully hereinafter in connection with the following description, and for a consideration of what I believe to be novel and my invention, attention is directed to the following specification and the claims appended thereto.

In the drawings, Fig. 1 is a side view of a structure embodying my invention; Fig. 2 is a face view thereof, partly in section to show the construction of certain parts; Fig. 3 is a sectional view taken on line 3—3, Fig. 2, and looking in the direction of the arrows; Fig. 4 is a detail sectional view on a larger scale showing one form of bearing arrangement; Fig. 5 is a face view, partly in section, of an embodiment of my invention particularly intended for outdoor use; Fig. 6 is a top plan view of the structure shown in Fig. 5; Fig. 7 is a face view, partly in section, of another construction embodying my invention, and Fig. 8 is a view of another modification.

According to my invention, I provide what may be termed a movable or a revolving golf hole, that is, a receptacle or pocket adapted to receive a golf ball comprising a wall which

projects above the surface on which the ball is rolled, the wall having an opening or entrance and being adapted to turn or move or to rotate on a vertical axis whereby the opening or entrance to the receptacle or pocket may be moved to face in different directions, the arrangement being such that the receptacle or pocket may be moved or turned by being struck by a ball. The receptacle or pocket is round preferably although it need not be necessarily, and it is provided preferably with one or more projections or protuberances which may be made with advantage from rubber of suitable hardness and which are adapted to be struck by a ball to effect movement of the structure.

Referring to the drawings, Figs. 1 to 4 inclusive show an embodiment of the invention intended particularly for use indoors. In these figures, 1 indicates a base ring adapted to be set on or to be embedded in the surface on which the game is to be played. On base ring 1 is mounted a ring 2 which is adapted to turn or rotate on ring 1. Any suitable bearing arrangement may be used between the two rings, the essential thing being that ring 2 may turn on ring 1 with the desired degree of freedom. In the present instance I have illustrated a ring of balls 3 between the two rings, thus forming a ball bearing. Carried by ring 2 is a wall 4 which may be in the form of a dome having a cut away portion which provides an opening 5. Dome 4 is formed from a suitable material such as a suitable metal, and may be integral with ring 2 or formed separately therefrom and suitably fastened thereto. In the present instance it is shown as being formed separately from ring 2 and welded thereto as is indicated at 6. Opening 5 is of a width somewhat less than half the dome 4 so that it lies on one side of the dome although it may be wider if found desirable. Fastened in the wall of the dome at the edges of the opening and at spaced intervals around the dome are projections or protuberances 7 located at a height such that they are adapted to be struck by a ball rolling on the surface surrounding the dome. The two projections 7 at the edges of the opening are turned at an

angle as is shown in Fig. 3. The others are fastened directly on the outer surface of the dome.

The rings 1 and 2 define a hole or pocket 8 adapted to receive a ball, the entrance to the hole or pocket being through the opening 5. The two rings 1 and 2 and the dome 4 are all fastened together to form a unitary structure adapted to be positioned on a floor, and the parts have sufficient weight so that when positioned on a floor ring 1 will remain stationary and the ring 2 and the dome will turn thereon.

When the revolving hole is to be used, it is positioned so that the surrounding surface is flush with the top of ring 2, that is, with the bottom edge of the opening. This may be accomplished by locating the ring in an opening in the material which provides the surrounding surface, the opening being of a depth to bring the ring 2 and the surface flush. When the revolving hole is to be positioned on top of a surface, for example, when it is to be placed on a carpet or rug in a room, I provide a tapered collar 9 which surrounds rings 1 and 2 and has an inclined top surface 10, the inner edge of which is flush with the top of ring 2 and the outer edge of which is at the level of the surface upon which the collar rests. Collar 9 is spaced slightly from ring 2 so as not to interfere with turning movements of ring 2 and the dome.

The revolving hole may be used by one person for practising putting or it may be used by two or more persons for a competitive game. When used as a competitive game, a feature of the game is that of a player rolling his own ball through the opening into the pocket or hole and at the same time striking with his ball one of the projections 7 to rotate the dome so as to turn the opening to face in a direction away from his opponent's ball. This will require then that his opponent must roll his ball to a position in front of the opening before he can roll it through the opening, thus being required to use an extra stroke. Various rules may be formulated for playing games with the revolving golf hole, the rules making use in various ways of the revolving feature of the hole.

A single revolving hole may be used for a game or two or more revolving holes suitably spaced from each other around a floor or other surface may be used. In case a game is to comprise two or more revolving holes, the several revolving holes may be made of different sizes and constructed so that the different domes offer different amounts of resistance to turning. This serves to lend variety to the game.

The revolving holes may be installed in connection with indoor miniature golf courses in which case the collars 9 need not be used, the dome being set down in the material form-

ing the putting surface so that the top of ring 2 is flush with the putting surface. When used as a part of a miniature golf course, it serves to add difficulty to the rolling of a ball into the hole and, due to the turning of the opening to face in different directions, to provide an additional hazard.

When the device is to be used out of doors, the construction is such that the revolving dome or wall is positioned over a hole in the ground, the opening in the dome or wall forming an entrance to the hole. Any suitable arrangement may be used for accomplishing this result, the arrangement being such, preferably, that the dome can be adjusted vertically so as to position correctly the opening in the dome.

Figures 5 and 6 show a construction well adapted for use out of doors in connection with a regular golf course or putting green, in connection with a miniature golf course, or on a lawn. In these figures, the dome 12 having the opening 13 for passage of a ball is provided with a depending threaded collar 14 which threads into a threaded liner 15 positioned in a hole 16 in the ground. The surface of the ground is indicated at 17 and collar 14 is screwed down into liner 15 until the lower edge 18 of opening 13 is flush with the surface of the ground. Collar 14 and liner 15 thus form a vertically adjustable support for the dome which enables the opening in the dome to be adjusted readily to correct position. In this construction the dome is made in two pieces hinged together as is indicated at 19. This enables the upper portion of the dome to be raised for removing balls from the hole. Also, the top of the dome is provided with an opening 20 through which a flag staff may be inserted. 21 indicates the staff support at the bottom of the hole. This adapts the dome for use on a regular golf course. 22 indicates the projections on the dome corresponding to the projections 7 of Figs. 1 to 4, and 23 indicates the bearing support for the dome.

In Fig. 7 is illustrated a modification wherein the dome 24 is supported on a ball bearing 25 on the top of a post 26. Post 26 is supported in a staff support 27 at the bottom of a hole 28 in the ground. The post is provided with an adjustable collar 29 at its lower end which serves to position the dome relatively to the surface of the ground. On the top of the dome is a knob by means of which it may be lifted from the hole and replaced therein. This construction is well adapted for use on a putting green or on a lawn. Otherwise the construction shown in Fig. 7 may be similar to that shown in Figs. 5 and 6.

It will be seen that with the construction shown in either Figs. 5 and 6 or Fig. 7, the dome may be readily removed from the hole and replaced therein so that at any time it

may be used or not as found desirable. When used on a regular golf course, the revolving hole adds an additional hazard and adds to the skill required for rolling the ball into the hole. Also, it enables a player in putting to so strike the dome as to revolve it to a position where the opening in the dome points in a direction away from his opponents ball, thus making it more difficult for his opponent to hole out.

10 While I have shown the wall which defines the revolving golf hole as being dome shaped, and while this is the shape I prefer, it is to be understood that my invention is not limited to the use of this shape but that other shapes may be used.

15 In Fig. 8 is shown a form of my invention wherein the wall or dome 31 is supported on suitable rollers or casters 32, the opening 33 in the wall or dome extending to the lower edge thereof so that a ball may be rolled through it. On the wall or dome are projections 34 adapted to be struck by a ball for turning or moving the structure. This construction is well adapted for use indoors on a rug or carpet.

20 By my invention I provide a movable or revolving golf hole which is simple in structure and readily adapted for use in a variety of ways as already explained. It may be made in different sizes and shapes and provided with projections formed in any suitable way, the essential thing being that the projections are adapted to effect movement of 25 the structure when struck by a ball. Also, the openings may be made in different sizes and arranged in different ways to meet any particular conditions. The structure lends itself to being made up in attractive colors and in sets of two or more as found desirable.

30 In accordance with the provisions of the patent statutes, I have described the principle of operation of my invention together with apparatus which I now consider to represent the best embodiments thereof, but it is to be understood that the constructions shown are only illustrative and that the invention may be carried out by other means.

35 What I claim as new and desire to secure by Letters Patent of the United States is:—

40 1. In a game structure, the combination of a wall which defines a pocket, said wall having an opening for the passage of a ball into the pocket, and means for rotatively supporting said wall with the lower edge of the opening flush with a surface over which a ball is to be rolled, whereby said wall may rotate to cause the opening to face in different directions.

45 2. In a game structure, the combination of a dome having an opening in one side through which a ball may be rolled, and means for rotatively supporting said dome with the lower edge of said opening flush with a surrounding surface over which a ball

is to be rolled, said dome being open at its bottom whereby it may be supported over a pocket so that a ball rolled through the opening will fall into such pocket.

50 3. In a game structure, the combination of a wall which defines a pocket, said wall having an opening for the passage of a ball into the pocket, means for rotatively supporting said wall with the lower edge of the opening flush with a surface over which a ball is to be rolled, and projections on said wall adapted to be struck by a ball for rotating the wall to cause the opening to face in different directions.

55 4. In a game structure, the combination of a dome having an opening in one side through which a ball may be rolled, means for rotatively supporting said dome with the lower edge of said opening flush with a surrounding surface over which a ball is to be rolled, said dome being open at its bottom whereby it may be supported over a pocket so that a ball rolled through the opening will fall into such pocket, and spaced projections around the lower portion of the dome adapted to be struck by a ball for rotating the dome.

60 5. A dome adapted to be supported over a hole in the ground, said dome having an opening in one side through which a ball may pass into the hole, and means for rotatively supporting the dome over a hole with the lower edge of said opening flush with the surface of the ground.

65 6. A dome adapted to be supported over a hole in the ground, said dome having an opening in one side through which a ball may pass into the hole, means for rotatively supporting the dome over a hole with the lower edge of said opening flush with the surface of the ground, and means whereby said supporting means may be adjusted vertically.

70 7. In combination, a wall which defines a pocket, said wall having an opening through which a ball may be rolled into the pocket, and a base member upon which said wall is rotatively mounted, said base member being adapted to support said wall with the lower edge of said opening flush with a surface over which a ball is to be rolled into the pocket.

75 8. In combination, a wall which defines a pocket, said wall having an opening through which a ball may be rolled into the pocket, a base member upon which said wall is rotatively mounted, said base member being adapted to support said wall on a flat surface, and a tapered collar which surrounds the base member with its top inner edge flush with the lower edge of said opening whereby it provides an inclined surface leading from the flat surface to said opening.

80 9. In combination, a ring adapted to be supported in fixed relation to a flat surface, an annular wall rotatively mounted on said ring, said wall being provided with an open-

ing through which a ball may be rolled, and means forming projections at the side edges of said opening adapted to be struck by a ball for rotating the wall.

10. The combination with means defining a recess for the reception of a ball, of a structure rotatively mounted over said recess and provided with an opening for the passage of a ball into the recess, and projections on said structure at the edges of said opening and spaced around the structure adapted to be struck by a ball for rotating the structure.

11. A structure comprising a wall which defines a pocket, said wall having an opening for the passage of a ball into the pocket, roller means for supporting said wall, and projections on the wall in spaced relation to each other adapted to be struck by a ball for turning the structure.

20. In witness whereof I have set my hand this
31 day of January, 1931.

CHARLES A. HOWLAND.
